FORM CLAMP

William H. Jenkins, El Monte, Calif.

Application August 26, 1940, Serial No. 354,201

4 Claims. (Cl. 85—49)

This invention relates to a novel means for use in securing the members of a concrete form in operative positions.

In the usual practice concrete form sheathing members are usually secured to the studs by nailing. This requires considerable time and labor in erecting and dismantling and further results in great waste of lumber. The present invention seeks to overcome these disadvantages and at the same time eliminate hammer marks and nail heads on the inside of the form.

The general object of the invention is therefore, to provide a novel clamp for securing the sheathing to the studs in concrete forms.

Another object of the invention is to provide a novel form clamp which does not require nailing.

Another object of the invention is to provide a novel form clamp adapted to engage studs which vary somewhat in dimensions.

Another object of the invention is to provide a novel form clamp wherein the stress in the clamp is relieved as the concrete is poured.

Another object of the invention is to provide a novel form clamp which may be used repeatedly; does not come into contact with the concrete; requires no special tools to install, and which may be installed in cramped locations.

Other objects and the advantages of the invention will be apparent from the following description taken in connection with the accompanying drawing, wherein:

Fig. 1 is a perspective view showing my novel form clamp in use;

Fig. 2 is a side elevation of the clamp;

Fig. 3 is an end view of the clamp shown in Fig. 2;

Fig. 4 is a fragmentary top plan view showing the clamp installed and in open or preliminary position;

Fig. 5 is a top plan view showing the clamp installed and in closed position;

Fig. 6 is a side elevation showing the clamp installed; and

Fig. 7 is a sectional view taken on line 7—7 of Fig. 2.

Referring to the drawing by reference characters I have shown my invention as embodied in a form clamp which is indicated generally at 10. As shown in Figs. 1 to 7 the device 10 includes a fastening member 11 engageable with the sheathing 12 of a concrete form and a member 13 hinged to the portion 11 as by a rivet 14 and resiliently engageable with studs 15.

The clamp 16 is preferably stamped from suit-

able material such as sheet steel and may be plated or otherwise treated to prevent corrosion. Certain portions may be hardened or otherwise heat treated.

As shown, the fastening member 11 has a tapered front end portion 16 and at the rear has a pair of sharpened points 17 bent in opposite directions to engage an upper and a lower sheathing board as shown.

10 The stud engaging member 13 includes side portions bent to form a rib 18 to receive the fastening member 11, therebetween. The member 13 further includes flange portions 19 engageable with the face or edge of a stud and a resilient end portion 20 engageable with the rear surface of a stud. The resilient portion 20 is rounded as at 21 and may include an aperture 22 to receive a nail (not shown) to prevent accidental disengagement of the clamp. The rib 18 continues onto the end portion 20 to reinforce the same.

In the use of my form clamp, the studs are erected in the usual manner and the bottom sheathing board secured thereto as by nailing.

25 A row of form clamps is then secured to the bottom sheathing board, one clamp adjacent every second stud. The members 13 are then pivoted into engagement with the stud. Another sheathing board is then laid above the first, being secured to the studs by the clamps. Another row of clamps are then positioned in the upper edge of the second board and in place. Other boards are added in a similar manner. Adjacent clamps on the same stud are positioned on 30 opposite sides of the stud to prevent lateral movement thereof.

It will be seen that the sheathing is firmly engaged by the bent portions 17 which are imbedded therein and that the sheathing is urged 40 tightly against the studs by the resilient portions 20. It will be further seen that the clamp permits variation in the dimensions of the lumber used. The inside of the form is free from nail heads and hammer marks and a smooth concrete face results.

In dismantling, the sheathing boards are merely pulled upwardly away from the clamps and the clamps disengaged from the studs. The lumber and clamps may be used repeatedly.

50 From the foregoing description it will be apparent that I have invented a novel clamp for concrete forms which is highly efficient for its intended purpose.

Having thus described my invention, I claim:

1. In a form clamp, an elongated body mem-

ber including a flat body having an outwardly projecting hollow flanged rib thereon, said body having an end portion extending at an angle to the rib, a securing member disposed within the rib and pivotally connected to the body portion, said securing member having securing prongs thereon.

2. In a form clamp, an elongated body member including two side portions, said side portions being spaced apart to form a rib, a flange on each side portion and extending outwardly therefrom, said body having an end portion extending at an angle to the rib, a securing member disposed between the ribs and pivotally connected to the body portion, said securing member having securing prongs thereon extending in opposite direction therefrom, said securing member at the end remote from said prongs having an inclined edge and said rib being inclined to correspond to the inclination of the inclined end on the securing member.

3. In a form clamp, an elongated body member including a groove forming rib having flanges thereon, said body member having an end portion extending at right angles to the flanges, said rib extending into the end portion to reinforce the same, a securing member disposed within said rib and pivotally connected to the body portion,

said securing member having securing prongs thereon extending in opposite direction therefrom, said securing member at the end remote from said prongs having an inclined edge and said rib being inclined to correspond to the inclination of the inclined end on the securing member.

4. In a form clamp, an elongated body member including a groove forming central rib having flanges extending therefrom, the flanges being disposed at right angles to the rib, said body having a hook like stud engaging end portion thereon extending at right angles to the flanges, said rib extending into the end portion to reinforce the same, a securing member disposed in said rib and pivotally connected to the end of the body portion remote from said end portion, said securing member being coplanar with said rib and having integral securing prongs thereon extending in opposite direction therefrom and disposed at right angles to the body of the securing member, said securing member at the end remote from said prongs having an inclined edge and said rib being inclined to correspond to the inclination of the inclined end on the securing member.

WILLIAM H. JENKINS.
